UNITED STATES PATENT OFFICE.

JOSEPH DI SILVESTRO, OF PHILADELPHIA, PENNSYLVANIA, ASSIGNOR TO AMERICAN WOOD TURNING CO., OF PHILADELPHIA, PENNSYLVANIA, A FIRM COMPOSED OF CHARLES OZLEK, HERMAN OZLEK, AND MOSES I. OZLEK.

DESIGN FOR A SPINDLE FOR LAMPS.

Application filed November 6, 1925. Serial No. 15,372. Term of patent 7 years.

To all whom it may concern:

Be it known that I, JOSEPH DI SILVESTRO, a citizen of the United States, residing at Philadelphia, in the county of Philadelphia and State of Pennsylvania, have invented a new, original, and ornamental Design for a Spindle for Lamps, of which the following is a specification, reference being had to the accompanying drawing, forming a part thereof, in which—

Figure 1 is an elevational view, and Figure 2 is a top plan view of said spindle for lamps showing my new design.

I claim:

The ornamental design for a spindle for lamps as shown.

JOSEPH DI SILVESTRO.
